HAIRPIN OPENER

Nye K. Eward, Altadena, Calif.

Application September 22, 1947, Serial No. 775,459

5 Claims. (Cl. 132—1)

1

The present invention relates to hair pin openers in general and in particular to an opener for that type of hair pin commonly known as the "bobby" pin. More specifically the invention comprises an opener by the use of which "bobby" pins may be spread with one hand while the user's other hand secures a curl previously arranged.

The modern woman freely uses hair pins to secure her hair in place, curls, ringlets, etc., being so retained. In recent years the common hair pin with corrugated sides has been supplemented by a modified pin, rectangular in section, known as a "bobby" pin. This pin is somewhat stiffer than the ordinary hair pin and is folded back upon itself; one of its sides usually being corrugated as in the older type. The two sides normally make contact adjacent their outer ends, the end of the corrugated side angling outwardly.

A "bobby" pin, however, must be opened in the sense that its sides or legs, which are held together by its own resilience, must be pried apart in order that it can be placed in securing relationship to the hair and this operation presents a continuing minor problem. Ordinarily a woman will arrange her hair with both hands and, while holding it in place with one hand, open the "bobby" pin with the other and then position the pin. Unfortunately, however, the pin cannot be opened easily with the fingers of one hand and accordingly the user relies upon supplementary means. Some pry the sides apart using the teeth, a performance which is particularly dangerous in that it scratches the enamel and can do serious injury. Others prefer to make use of the edge of the dresser, which operation is also objectionable in that inevitably that piece of furniture is scratched and marred. Some prefer, however, to open the pin by inserting a finger nail between its ends, and in doing so scratch and mar their finger nail polish. The problem of opening "bobby" pins in an easy and satisfactory manner is one which has heretofore escaped satisfactory solution.

With an appreciation of the shortcomings of the methods which have heretofore been used in opening "bobby" pins, and in order to provide a superior method and a device for the accomplishment thereof, it is a primary object of the present invention to provide a simple and economically manufactured unit by the use of which a "bobby" pin can readily be opened without skill and with one hand.

It is another object of the invention to provide a simple "bobby" pin opener including no moving

parts, and which functions to open the pin automatically as it is moved relative thereto.

Still another object of the invention is to provide a "bobby" pin opener which is suitable for use with a variety of "bobby" pins available upon the market.

A further object of the invention is to provide a device to open "bobby" pins adapted to be carried in a lady's hand bag.

10 A still further object of the invention is to provide an opener for "bobby" pins in which the surfaces are so related that the forces exerted do not effect the movement of the device over a supporting surface.

These and other more specific objects will appear upon reading the following specification and claims and upon considering in connection therewith the attached drawings to which they relate.

15 20 Referring now to the drawing in which preferred embodiments of the invention are disclosed:

Figure 1 is a top view of the metallic target element forming a principal part of the opener constructed in accordance with the first preferred embodiment of the invention;

Fig. 2 is a top plan view of the base element adapted to the support of the target element of Figure 1;

Figure 3 is a vertical section through the unit constructed in accordance with the first preferred embodiment of the invention with the target positioned in the base;

Figure 3A is an enlarged fragmentary section of the showing of Figure 3;

Figure 4 is a section similar to Figure 3 through a second preferred embodiment of the invention;

Figure 5 is a vertical section through a third preferred embodiment of the invention adapted to be carried upon the wrist of the user;

Figure 6 is an end view of the construction of Figure 5; and

Figure 7 is a transverse section through still another embodiment of the invention in which the target element is fixedly secured to a supporting surface.

Referring again to the drawings and to Figures 1, 2, and 3 inclusive, in particular, the first preferred embodiment of the invention is illustrated and is seen to comprise a target element indicated generally by the reference character 10 and a base element indicated generally by the reference character 11. Target element 10 is formed with end portions 12 and 13 extended in planes at right angles to each other. Adjacent to por-

tion 12 target area 14 of element 10 slopes downwardly as viewed in Figure 3 making an angle of 35° with the plane of end 13. This sloping section is indicated by the reference character 14 and comprises the target area proper. Adjacent to end portion 13 and extending at an obtuse angle relative to the plane thereof is an intermediate section indicated by the reference character 16. Sections 14 and 16 are joined by a curved surface or section 17 comprising an arc of a circle to which section 16 lies tangent, a transverse elongated slot 18 lying in the plane of the target area 14 and separating that area from section 17. Converging raised guides 19 are positioned upon target area 14 and converge toward the slot 18 in the manner clearly illustrated in Figure 1 to insure that a moving object traveling along the surface in the direction of the slot will be directed thereto.

Slot 18 may be formed in any suitable manner as by stamping, the turned-over edges preferably extending interiorly, that is, into the angle formed by the sides 14 and 16. Slot 18 may have different widths and lengths, but its width, preferably is directly proportional to the thickness of a "bobby" pin and inversely proportional to the sine of the angle of incidence which the pin makes with the plane of the target area 14. A range of 35 degrees to 90 degrees is reasonable for this angle. The maximum slot width, of course would be that which obstructs the movement of a "bobby" pin relative thereto in the sense that one side of the pin would strike there against as the other side entered. Stated differently, the minimum width of the slot is that width which enables one side of the pin to slide therethru as it is moved along the target area while angularly related thereto at the minimum practical angle; the maximum width being that which is slightly less than that which enables both ends of the pin to pass therethru with the pin advancing normal to the plane of the slot.

Referring now particularly to Figure 2 the base element 11 in which the target element 10 is mounted is illustrated as substantially elliptical in shape, although any preferred contour may be selected. In a preferred form the base is made of a material such as rubber or a synthetic equivalent which will not slide readily upon a supporting surface although it is to be understood that the lower surface only may be so formed. Base 11 is provided with a transverse slot 21 in which the end section 13 seats and in the preferred embodiment illustrated, a rectangular recess 22 is formed adjacent thereto and forwardly thereof as illustrated in Figure 3.

In opening a "bobby" pin by the use of the construction illustrated in Figures 1 to 3 inclusive, the pin is grasped between the thumb and forefinger and moved longitudinally downwardly until its adjacent end strikes the target area 14. The guides 19 perform their function and direct the downwardly moving pin toward slot 18 should it be positioned laterally at either side thereof. As the pin continues its downward movement its end riding upon the target area enters the slot 18 thereupon the advancing edge of the slot extends between the sides of the pin the upper or outer side of which then rides in tangency to the curved surface 17. Continued downward travel moves the side or leg extending through the opening 18 against the inner side of section 16, the opposite side of the pin riding around upon the exterior surface of the curve 17. The pin pivots in a counterclockwise direc-

tion from the vertical position illustrated in Figure 3 and is opened as its movement continues in accordance with the theorem of Pythagoras, in which "An angle formed by a secant and a tangent, drawn to a circle from an external point, is measured by half the difference of the intercepted arcs." Applying this theorem, as the one side of the pin pierces the target plane and becomes a chord of the arc formed by circle portion 17, it also becomes a secant, while the outer side of the pin rides tangent to the same surface. As the pin advances through the opening 18, and as the chord increases in length, it follows that the angle between the sides of the pin will also increase to effect the desired spreading. The presence of the recess 22 provides additional clearance.

With the pin spread as described the operator retains it tightly between the two supporting fingers, the fleshy parts of the finger pads aiding in the operation. The pin is then withdrawn from the target element and positioned in the hair to perform its intended function.

Referring now to the embodiment of the invention illustrated in Figure 4, the element 11 is seen to be similar to that element in the first embodiment with the exception that the recess 22 has been omitted. In place of the target element 10 of the first embodiment there is substituted a target 30 which is seen to comprise a surface 31 sloping slightly downwardly and interrupted between its ends by a transverse slot 32 corresponding to slot 18 of the first embodiment and through which one side of a pin may extend. Surface 31 is connected by a curved surface 33 with a reversely sloping surface 34 so positioned and related to slot 32 that a pin side passing downwardly therethru will strike surface 34 and be deflected downwardly, its continued advance effecting a spreading action in an obvious manner. Downwardly extending end sections 35 and 36 seat removably in transverse slots 37 and 38 in base 11. This embodiment may be provided with converging guides similar to the guides 19 of the first embodiment if desired.

In the use of the opener constructed in accordance with this second embodiment of the invention the "bobby" pin is again grasped between the thumb and the forefinger, preferably about one-third of its length from its closed end. The pin is moved downwardly until its adjacent end strikes the target area 31. Continued downward movement causes the adjacent end, which is preferably the straight end, to enter the slot 32 while the opposite side rides upon the curved surface 33. Upon the further downward movement that end of the pin which has passed through the slot 32 strikes the reversely sloping surface 34 and is deflected downwardly to tilt the pin into a more nearly vertical position, whereupon its side riding in contact with the target area 31 rounds the curved surface 33 effecting a spreading of the pin by a desired optimum angle.

Referring now to Figures 5 and 6 in particular, the third preferred embodiment of the invention is illustrated and is seen to comprise a target element indicated generally by the reference character 40. The transverse slot, corresponding to slot 18 of the first embodiment, is here indicated by the reference character 45. Basically this embodiment is similar to the target element 10 of the first embodiment with the exception that it is triangular in longitudinal section, the end sections 12 and 13 being replaced by underlying flat section 41 fixedly secured to a bracelet

clamp 42 which may be of a size to encircle the wrist or the knee of the user. A magnet 43 is also carried by bracelet 42 which may itself be magnetized if desired. Pins may be picked up readily by lowering the unit into a pin-containing receptacle to enable the pins to adhere to the magnetized surfaces. The opening of a pin by the use of this embodiment of the invention corresponds to the opening operation as described in the first embodiment with the exception that the pin is advanced horizontally rather than vertically.

Referring now to the Figure 7, the fourth preferred embodiment of the invention is seen to comprise a target element 50 including a target area 51 which merges through a circular arc 52 with a back section 53, a slot 54 being provided at the upper extremity of surface 51 and lying in the plane thereof. Feet or abutments 56 and 57 are provided at the ends of section 51 and 53 and are secured to a supporting surface 58 by means of screws 59. The uses of this embodiment of the invention are obvious from the discussion given above in connection with the preceding embodiments and it is clear that the device may be mounted upon a horizontal surface or upon a vertical surface.

In the first two embodiments the pin is moved downwardly into contact with the opener and the forces expanded are primarily directed downwardly so that there is no appreciable tendency to move the unit laterally upon a supporting surface. This relationship is desirable in that it enables the unit to be made of light material with a resulting saving in manufacturing costs. The third and fourth embodiments illustrated in Figures 5, 6, and 7, respectively, accomplish the opening of the pin by a horizontal movement, but in each case the target element is suitably supported to prevent sliding movement.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. An opener for bobby pins and the like comprising a target element in the form of an elongated unitary strip of thin bendable material of substantially uniform width and thickness, said strip including a plurality of successive interconnected sections of varying inclinations, said strip

having end means for securing the target element to a suitable base, with the successive sections disposed at varying inclinations to each other and to the base, said target element includ-

- 5 ing as adjacent sections a flat target section inclined at an oblique angle with reference to the base and serving as a guide surface for a leg of a bobby pin or the like to be opened, and a curved spreading section forming a continuation of the 10 flat section and inclined thereto, said target element being transversely slotted substantially at the line of juncture of said flat and curved surfaces, said slot being of sufficient width to receive the end of the leg of the bobby pin as it is advanced along said inclined target section, while said curved spreading section serves to deflect and guide the end of the other leg of the bobby pin and thereby spread the pin to open position.

2. A bobby pin opener or the like as set forth 20 in claim 1, wherein one end only of the target element strip is supported on the base.

3. A bobby pin opener as set forth in claim 1, wherein both ends of the target element strip are supported on the base and the adjacent 25 sections comprising the flat target section and the curved spreading section are generally inclined downwardly in opposite directions toward the base from approximately their line of juncture.

30 4. A bobby pin opener as set forth in claim 1, wherein both ends of the strip comprising the target element are detachably secured to the base.

5. In a device of the class described, a target 35 providing a surface, means providing a flat spreading surface spaced from said target surface by a transverse slot of a width to receive one leg only of a bobby pin, said target being provided with guide walls at the sides of its surface converging toward said slot to insure that 40 the end of a bobby pin leg sliding therealong will enter said slot, and being further characterized in that said device is unobstructed below said slot so that said pin after passing through said slot can be pivoted freely to effect its opening.

45 NYE K. ELWARD.
